[57] CLAIM

The ornamental design for a desk top, as shown and described.

DESCRIPTION

FIG. 1 is a rear perspective view of a desk top showing my design;

FIG. 2 is a top view;

FIG. 3 is a side perspective view; and

FIG. 4 is a front perspective view thereof taken slightly in perspective.

The side of the desk top not shown is a mirror image of the side shown in FIG. 3.

FIG. 1

FIG. 2

FIG. 4
